US0D1077891S

(12) **United States Design Patent** (10) **Patent No.:** **US D1,077,891 S**
(45) **Date of Patent:** **** Jun. 3, 2025**

(54) **PROJECTOR**

(71) Applicant: **Shenzhen Baishi Connected Technology Co., Ltd.**, Shenzhen (CN)

(72) Inventor: **Lu Peng**, Shenzhen (CN)

(73) Assignee: **Shenzhen Baishi Connected Technology Co., Ltd.**, Shenzhen (CN)

(**) Term: **15 Years**

(21) Appl. No.: **29/987,135**

(22) Filed: **Jan. 21, 2025**

(30) **Foreign Application Priority Data**

Sep. 3, 2024 (EM) 015071199-0001

(51) **LOC (15) Cl.** **16-02**

(52) **U.S. Cl.**

USPC **D16/229**

(58) **Field of Classification Search**

USPC D16/221, 225, 230, 231, 234; D21/514

(57) **CLAIM**

The ornamental design for a projector, as shown and described.

DESCRIPTION

FIG. 1 is a front perspective view of a projector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the projector, which form no part of the claimed design.

1 Claim, 8 Drawing Sheets
